UNITED STATES PATENT OFFICE.

JAMES S. TAYLOR, OF PONCA CITY, OKLAHOMA, ASSIGNOR OF ONE-HALF TO LORY J. MILDREN, OF PONCA CITY, OKLAHOMA.

CABLE CLAMP.

Application filed October 23, 1926. Serial No. 143,690.

This invention relates to improvements in wire rope supporting clamps.

The primary object of this invention is the provision of an improved drilling clamp for the supporting of drill cables and the like, embodying improved means whereby an enormous pressure may be brought to bear upon a pair of clamping jaws.

A further object of this invention is the provision of an improved wire rope supporting clamp, including means to obtain practically a right angled purchase upon a drill cable or line, and the novel arrangement of mounting jaws upon a supporting body.

A further object of this invention is the provision of improved means for mounting the jaw constructions of a drill cable clamp, so that the jaw constructions will move absolutely in unison to secure a correct and uniform pressure upon the cable.

Other objects and advantages of this invention will be apparent during the course of the following detailed description.

In the accompanying drawings, forming a part of this specification, and wherein similar reference characters designate corresponding parts throughout the several views,

Figure 1 is a plan view, partly in section, of the improved wire cable clamp, showing the jaws of the same in clamping relation upon a cable.

Figure 2 is a fragmentary side elevation partly in section, of the improved wire rope supporting clamp in a clamping position.

Figure 3 is a transverse sectional view taken substantially on the line 3—3 of Figure 4.

Figure 4 is a sectional view taken substantially on the line 4—4 of Figure 1.

Figure 5 is a transverse sectional view similar to the view illustrated in Figure 3, with the jaw parts of the clamp in an open relation.

Figure 6 is a perspective view of a novel type of clamping jaw embodied in this invention.

Figure 7 is a perspective view of the manner of mounting each jaw in the body of the clamp.

In the drawing, wherein for the purpose of illustration is shown only a preferred embodiment of the invention, the letter A

may generally designate the improved clamp which may include a supporting body 55 B, having clamp jaws C and D pivotally mounted thereon for the gripping of a cable E; means F being provided for relatively adjusting the location of the jaws C and D in the body B, for clamping and clamp 60 release purposes.

The body B, as well as other parts of the invention, is made of durable metal construction, of a nature best adapted to support the heavy load of the cable and drill tools. The body B includes the substantially concavo-convex portion 10, having one

face thereof concaved, and at opposite side edges thereof the same being provided with forwardly extending flanges 12 and 13, 70 throughout the height of the portion 10, to define a channel 14, as illustrated in Figures 2 and 3 of the drawings. Each of the flanges 12 and 13, on the facing sides thereof, is provided with upper and lower convex extensions 15 and 16, and a relatively longer intermediate convex extension 17, all

of which extensions are apertured at 18 in aligning relation, for receiving jaw pivot pins 19 therethrough, for pivoting the jaws 80 C and D thereto as will be subsequently mentioned. The jaw extensions 15, 16 and 17 of each body flange 12 and 13, are spaced, providing the space 21 between the upper and intermediate extensions, and 85

the space 22 between the lower and intermediate extensions, and which spaces are adapted to receive the segmental externally convexed extensions 23 and 24 respectively, of the jaws C and D, as will be subsequently described. The top and bottom surfaces of the body B are preferably flat and parallel, and the body B, preferably at the flanges 12 and 13, is provided with upstanding hooks 29 and 30, respectively on the 95 flanges 12 and 13, which are extended laterally beyond the outer surfaces of the flanges 12 and 13 in a nonobstructing relation with respect to the channel 14 of the body B, extended, and which hooks 29 and 30 are 100 adapted to receive the conventional reins for suspending the drill clamp from the temper screws of the well drilling apparatus.

The jaw constructions C and D are formed 105 in lefts and rights respectively, and have

their respective bearings on the flanges 12 and 13. These jaws are of the same general construction, including the main portion 35, provided with one side edge thereof concave at 36, longitudinally thereof, from the top surface to the bottom surface of the main portion 35; the segmental extensions 23 and 24 above mentioned projecting beyond the concavity 36, for fitting in the spaces 21 and 22 of the flanges 12 and 13 of the body B, above mentioned. The radius from which the concavity 36 is formed, is equal to the radii of the convex edges of the extensions 15, 16 and 17 above mentioned, so that the jaw constructions C and D have an accurate bearing on the body B, for pivotal action. When the jaws C and D are assembled on their respective bearing flanges 12 and 13 of the body B, the aligning apertures 18 of the extensions 15, 16 and 17, and apertures of the jaw bearing extensions 23 and 24 receive the pintle pins 19 above described, to positively pivot the jaws C and D on pivot axes which will not shift. Notwithstanding the provision of the pintle pins 19, the wear does not take place upon these pintle pins, but takes place upon the convex surfaces of the extensions 15, 16 and 17 bearing in the concave surfaces 36 of the jaw main portions 35, as is illustrated in the various views of the drawing.

Each of the jaw constructions C and D includes the relatively long arm 40 extending therefrom, which are adapted to lie substantially at right angles to a line drawn between the pintle pins 19 of said jaws C and D, when the jaws are closed. These arms 40 gradually increase in thickness from their outer ends towards the main portions 35 of the jaws, and the main portions of the jaws are of course thicker than any portion of the arms 40, as is illustrated in the drawing. The jaws C and D on their facing sides of the main portions 35 are provided with concavities 45 and 46^a respectively longitudinally thereof, which receive therein liners 46. The liners 46 are as illustrated in Figure 4 of the drawing, the same being elongated, of concavo-convex formation, having the upper ends thereof flanged at 48 to overlie the top surfaces of the jaws C and D, in order to properly support said liners. Each of the liners 46 intermediate the ends thereof is provided with a thickened portion 49, received within a suitable recess 51 provided inwardly of the concave surfaces 45 and 46^a of the jaws; the thickened portion 49 being provided with screw threaded openings 54 for receiving supporting and set screws 55, detachably carried by the main portions 35 of the jaws C and D, and adjustable from adjacent the juncture of the arms 40 with the portions 35, as illustrated in Figure 3 of the drawing, in order

to clamp and hold the liners in place in their respective recesses 45 and 46 of the jaws C and D. The liners 46 are concavo-convex in formation, and the same are complementary, to provide a passageway 55 therethrough, which may receive the wire cable E or other element; the passageway 55 being increased or decreased in size according to the relative pivoting of the jaw constructions C and D on the pintles 19, as is readily apparent.

The placement of the recesses 45 and 46^a and the disposition of the liners 46 therein is so located with respect to the pintle pins 19 of the jaws C and D, that when the jaws C and D are closed in a clamping relation upon the cable E, the passageway 55 will be intersected by a liner drawn from the pivot axis of one jaw to the pivot axis of the other jaw. In fact, in the device as used the most desirable arrangement is that when the jaws C and D commence to clamp upon the cable E to support the same, the center of the cable, or the center of the passageway 55 receiving the same, will be located about one-quarter of an inch forwardly from a line drawn straight between the pivot axes of the jaws C and D, and it is to be noted in this connection that the cable E is thus supported forwardly of the plane intersecting the pivot axes of the jaws C and D, at the opposite side of such plane from the body B. In this connection the cable receiving passageway 55 is entirely received within the channel 14 provided by the body B. This arrangement insures practically a right angled purchase of the lever-jaws C and D on the cable, so that as the jaws C and D are forced together the most powerful clamping action takes place immediately as the center of the passageway 55 approaches the straight line drawn between the pivot axes of the jaw constructions C and D, and due to the novel arrangement of parts the center of the passageway 55 may practically approach this straight line, but will never do so, due to the limiting movement which the convex rear surfaces 60 have upon the jaws, by engaging the concave surface 11 of the body B, as is illustrated in Figure 1 of the drawings.

The means F for clamping the jaws C and D upon the cable may include conventional constructions such as a yoke 65 pivoted on a pintle pin 66 which is supported on a lateral extending apertured portion 67 of one arm 40. The yoke 65 may be swung to receive the forward end of the other arm 40 therein, and the yoke 65 supports the clamp adjusting screw 68, which is supported in a screw threaded opening 69 of the yoke, so that the end 70 of said screw 68 may be set against a seat 71 at the outer side of the arm 40 of the jaw construction D, in order that the jaw constructions C and

D may be relatively moved together for clamping on the cable E, as is readily apparent.

Means is provided to insure an absolutely uniform opening and closing of the jaw constructions C and D, in order to produce an efficient uniform clamping action of both jaws on the cable E, and to avoid the eccentric pivot and clamping action which some types of clamps have upon the cable, very often resulting in the releasing of the cable when the jaws relatively move to adjust themselves to the strain of supporting the cable. In order to provide for such uniform movement of the jaws I construct the jaw body 35 of the jaw construction D with a finger 74 located on the face of the portion 35 thereof which faces the portion 35 of the other jaw, which extends beyond the plane of the side of the main portion 35 of the jaw construction D, and it is adapted to operate in a suitable recess 75 provided in the portion 35 of the construction C, inwardly of the face of the portion 35 of said jaw C which faces the concave surface 11 of the body B, so that the finger 74 may be said to engage behind the jaw construction C, in order that upon movement of the jaw construction D outwardly, the jaw construction C will be moved outwardly therewith.

In similar manner the jaw C is provided with a finger projection 80 in spaced relation below the recess 75 thereon, which extends beyond the plane of the groove in the liner 46, in order to engage in a recess or socket 81 provided therefor in the facing and rear surfaces of the body 35 of the jaw construction D. The faces of the projections 74 and 80 and the surfaces on which they ride in the sockets or recesses 75 and 81 are convexed, to facilitate operation, as illustrated in Figure 5.

From the foregoing description of the fingers or projections 74 and 80, and the manner in which they are relatively located on the jaws, it is apparent that any inner and outer movement of the jaws will be effected in the same degree, so that there cannot be any movement of either jaw without a similar movement of the other jaw.

It will be noted that the jaws are of the same height as the body portion B. This provides a very compact arrangement, and the fact that in the article as used the center of the passageway in which the rope is clamped is one-fourth of an inch from a straight line drawn between the two pivot axes of the jaw constructions provides what has been found to be the most efficient arrangement.

The jaws C and D are in rocking edge engagement during normal clamping and releasing action on the cable at a location behind the cable receiving grooves of the liners.

Various changes in the shape, size, and arrangement of parts may be made to the form of invention herein shown and described, without departing from the spirit of the invention or the scope of the claims. 70

I claim:

1. A cable clamp comprising a supporting body having spaced forwardly extending flanges, a pair of jaw constructions arranged on the body between said flanges, one of each of which bears on one of each of said flanges, said jaws and flanges being constructed to pivotally support the jaw constructions on definitely spaced axes, the jaws having the facing surfaces thereof provided with clamp receiving recesses, and means for moving said jaw constructions together or away from each other for clamping or releasing a cable with respect to said cable receiving recesses, the cable receiving recesses when in a cable clamping and receiving position having the center of said cable receiving recess disposed forwardly of a straight line drawn between the pivot axes of said jaw construction with the straight line eccentrically intersecting said cable receiving recess. 85

2. In a cable clamp the combination of a supporting body having spaced forwardly extending flanges to provide a channel 95 groove therebetween, jaws pivotally mounted in said channel groove upon the facing sides of said flanges, said jaws having cable receiving recesses defining a cable receiving passageway in the facing surfaces thereof, 100 means on the jaws rearwardly of said cable receiving passageway for insuring that the jaws will have uniform movement with respect to each other and with respect to the body, and means for relatively moving said 105 jaws into a cable clamping relation.

3. In a cable clamp the combination of a supporting body, a pair of jaws pivoted on the body, said jaws having cable receiving recesses to define a cable receiving passageway in the facing surfaces thereof, means on the jaw constructions at one side of said passageway for moving the jaws into a cable clamping relation, rigid projections on each of the jaws at the opposite side of the passageway from said last mentioned means respectively engaging behind the jaws on which they are not rigidly mounted, said projections and jaws having engageable convex surfaces to facilitate sliding. 110 115

4. In a cable clamp the combination of a supporting body, a pair of jaws pivoted on the body having recesses for receiving a cable, means to move the jaws into a clamping relation on the cable, each of said jaws 125 having notches therein at the opposite sides of the cable recesses from said last mentioned means, and each of said jaws having projections at the opposite side of the recesses from said last mentioned means for 130

engagement in the notches of the other jaws whereby to insure a uniform movement of the jaws with respect to the cable.

5. A cable clamp comprising a supporting body having spaced forwardly extending flanges to define a passageway therebetween, said flanges having recesses therein at their facing sides along the length thereof, said flanges having aligning apertured 10 projections intersecting said recesses, a pair of jaws, each of said jaws having spaced apertured ears for reception in the recesses of said flanges to align the apertures therewith with the apertures of said projections, 15 pivot pins pivoting the jaws on said flanges in the space therebetween, said jaws having facing grooves to define a cable receiving passageway, and means for relatively moving said jaws to expand or contract said passageway for cable clamp and release purposes.

6. In a cable clamp the combination of a

supporting body having spaced forwardly extending flanges to define a groove therebetween, a pair of jaws pivoted on said flanges 25 in the groove, said jaws having facing recesses defining a cable receiving passageway, means to move the jaws into a clamping relation, and upwardly extending receiving hooks on each of said flanges and 30 laterally opening and extending in an opposite direction from said jaws.

7. A cable clamp comprising a substantially channel shaped supporting body having a wide shallow channel passageway 35 therein, the body at opposite sides of the channel having apertured lugs projecting into the channel, and substantially L-shaped operating levers pivoted directly in said channel on said lugs, said operating levers 40 in the facing sides having grooves providing a cable receiving recess.

JAMES S. TAYLOR.
